REINHOLD RÜDENBERG, OF BERLIN-GRUNEWALD, GERMANY, ASSIGNOR TO SIEMENS-SCHUCKERTWERKE GESELLSCHAFT MIT BESCHRÄNKTER HAFTUNG, OF SIEMENS-STADT, NEAR BERLIN, GERMANY, A GERMAN CORPORATION.

ARRANGEMENT OR SYSTEM FOR OPERATING MECHANICAL RECTIFIERS FOR ALTERNATING CURRENT.

Application filed December 1, 1925, Serial No. 72,608, and in Germany December 12, 1924.

My invention relates to an arrangement or system for operating mechanical rectifiers for alternating current.

In mechanical rectifiers which convert high tension alternating current into direct current, strong sparking frequently occurs at the leading as well as at the trailing edge of the contact segments. Researches have proven that the sparking at the trailing edge is due to the fact that immediately after the contact break a considerable pressure difference develops between the two separating edges.

In the accompanying drawings I have illustrated my invention by graphs and by a wiring diagram,

Figs. 1 and 2 representing explanatory graphs which show the conditions generally existing during mechanical rectification,

Figs. 3 and 4 representing graphs illustrating the conditions existing according to the present improvement, and

Fig. 5 representing a diagrammatic illustration of a mechanical rectifier and its circuit connections according to the present invention.

The conditions usually existing during mechanical high voltage rectification as heretofore practiced are illustrated in Figures 1 and 2 of the drawing. The curve E in Fig. 1 is the voltage curve of the alternating current, the negative half having been turned upwards owing to the action of the rectifier usually provided. The rotating arms of the rectifier feed the consumer directly during the part E_k of this voltage shown in heavy lines. In the meantime the contact with the feeding transformer is interrupted and the consumer has only the natural voltage e determined by its capacity which after the contact is broken decreases in amplitude almost according to an exponential curve depending upon the size of the current consumer and the capacity. Generally the dropping of the voltage e at the consumer will take place with a different speed from the variation of the pressure E at the transformer. The pressure difference developing hereby is indicated in Fig. 1 by the vertical shading of the area between the curves E and e . This

pressure difference between the stationary and the rotating contacts causes the repeated sparking immediately after the separation of the contacts. The pressure difference increases particularly quickly immediately after the breaking of the contact, if the time constant of the natural voltage of the consumer is relatively small i. e. when the pressure e drops quickly.

In Fig. 2 another case is illustrated with a greater time constant of the consumer the moment of break being chosen at a time later than the occurrence of the pressure maximum. While in Fig. 1 the pressure e at the consumer has dropped quicker than the pressure E at the transformer, it drops considerably slower here. A great pressure difference develops in this case also between the contacts moving apart so that also in this case sparking occurs.

These drawbacks are eliminated according to my invention by choosing the time of contact separation at the rectifier so that the drop characteristic of the voltage applied and that of the natural voltage of the consumer substantially coincide about the time when the contacts separate. Such a characteristic is illustrated in Fig. 3 of the drawing. The voltage curve E and the curve of the natural voltage e possess at the moment when the contacts separate the same tangent t . In this case no pressure difference exists between the contacts travelling apart during a considerable period subsequent to the running off so that no sparking can occur.

If the transformer voltage E develops sinusoidally and the consumer voltage exponentially, the instant of time may be mathematically determined which must be chosen on the sinusoidal transformer voltage curve E for the separation of the contacts, so that at this instant the tangents to the sine curve and to the consumer voltage curve coincide. In the following T_3 represents the time for which the contact remains closed beyond the maximum value of the sine voltage (see Fig. 3). T represents the time constant determined by the capacity and the ohmic resistance of the consumer, by which in turn the decrease of the consumer voltage e after the contact break is

determined (Figs. 1-4). Accordingly the voltage values E and e and their differential quotients, which represent the tangents to the voltage curves, must be equal at the moment of contact separation. If ω represents the frequency of the alternating voltage supplied, t the period of time commencing with the voltage maximum, E_1 according to Fig. 3 the amplitude of the alternating voltage, and e_2 the ideal value of the consumer voltage during the same time period, then the transformer voltage may be expressed by:

$$E = E_1 \cosine \omega t \quad (1)$$

and its change by

$$\frac{dE}{dt} = -\omega E_1 \sin \omega t \quad (2)$$

20 The consumer voltage is on the other hand

$$e = e_2 e^{-\frac{t}{T}} \quad (3)$$

and its change

$$\frac{de}{dt} = -\frac{e_2}{T} e^{-\frac{t}{T}} \quad (4)$$

For the moment of running off the following equations of condition therefore hold 30 good

$$E_1 \cosine \omega \tau_3 = e_2 e^{-\frac{\tau_3}{T}}$$

$$\omega E_1 \sin \omega \tau_3 = \frac{e_2}{T} e^{-\frac{\tau_3}{T}} \quad (5)$$

From this follows by division

$$\cotangent \omega \tau_3 = \omega T \quad (6)$$

so that for each consumer with given time 40 constant T a definite most favorable running-off angle τ_3 is obtained. For the case illustrated in Fig. 3 the time constant T is equal to two thirds of the half wave period $T_1/2$.

45 Therefore is

$$\omega T = \frac{T}{T_1/2 \cdot \pi} = \pi \cdot \frac{2}{3} = 2.09 \quad (7)$$

so that for the most favorable running-off 50 angle we obtain

$$\omega \tau_3 = \text{arc ctg. } 2.09 = 25.5^\circ \quad (8)$$

In the design of the rectifier producing a voltage characteristic according to Fig. 3 55 of the drawing the sparking at the moment of running off is suppressed, but at the moment of contact closing a great voltage difference prevails between the natural voltage e and the transformer voltage E (indicated 60 in broken lines) and this gives rise to impact oscillations. In order to eliminate these impact oscillations the duration of the contact is according to my invention so adjusted that at the moment of the closing 65 of the contact the natural voltage is equal

or approximately equal to the voltage supplied by the transformer so that impact oscillations are effectively avoided.

Fig. 4 of the drawing illustrates such a characteristic. The voltage e and the alternating voltage E are equal at the moment of switching in. In the graph according to Fig. 4 the condition exists for the period τ_1 from the moment of starting up to the attainment of the pressure amplitude according to the equation

$$E_1 \cosine \omega \tau_3 e^{-\frac{\tau_3}{T}} = E_1 \cosine \omega \tau_1 \quad (9)$$

wherein the duration of the period during 80 which no contact exists is denoted by τ_2 . Since the sum of the three periods is equal to a half period of the alternating voltage, thus

$$\tau_1 + \tau_2 + \tau_3 = \frac{\pi}{\omega} \quad (10)$$

by insertion of τ_2 in the exponent of equation (9) and logarithming the equation of condition for the starting contact period τ_1 90

$$\ln \frac{\cos \omega \tau_3}{\cos \omega \tau_1} = \frac{\pi - \omega \tau_1 - \omega \tau_3}{\omega T} \quad (11)$$

is obtained.

Since according to equation (6) T_1 depends only upon the time constant, the running-on period T_1 is also solely a function of the time constant T .

It is advisable to choose the closing and breaking moment according to my invention 100 for the fully loaded consumer. If the load of the rectifier drops, the time constant of the natural voltage e also changes and this natural voltage e does now not drop as much as before so that impact oscillations may 105 occur again. These impact oscillations now pass to the negative side and can therefore not produce any considerable excess voltages. The operation of rectifiers with contact segments correctly dimensioned for full load 110 and adjusted according to my invention does therefore not lead to any disturbing secondary phenomena.

In Fig. 5 I have illustrated a mechanical rectifier and its associated circuits by which 115 the results hereinbefore discussed are obtained. In this figure, 1 represents an alternating current transformer whose primary is connected to the alternating current mains 11 and whose secondary produces high voltage. The secondary of this transformer is connected by way of the mechanical rectifier 15 and the consumer's lines 7 and 8 to a pulsating direct current consumer which may be of any character. It is indicated in 120 Fig. 5 by a rectangle labeled "pulsating D. C. consumer." This consumer receives the pulsating direct current produced by the mechanical rectifier 15 according to well known general principles. The shaft of 125 130

the rectifier is driven by means of a synchronous motor 6 connected likewise to mains 11. 2, 2' and 3, 3' are stationary contacts of the rectifier which represent 5 arcs of definite length determined according to the principles of my invention explained hereinbefore. These contact segments are connected with the high tension secondary of the transformer and with the consumer's 10 circuit, in the present case in such manner that the two ends of the high tension winding are connected to the two lower segments 2 and 3' whereas the consumer's line 7 is connected to the corresponding segments 2 and 15 3 the middle point of the high tension secondary being connected to ground. The consumer's line 8 is likewise grounded as shown at 13 so that in this manner both halves of the alternating current wave are 20 utilized for rectification in the well known manner. 4 and 5 respectively are the rotating contact arms for the segment pairs 2, 2' and 3, 3' and are mounted on the shaft driven by motor 6 in such manner that they are 25 transposed at an angle of 90° relatively to each other in order to obtain the rectification of both halves of the alternating current wave. These contact arms 4 and 5 are insulated from the shaft by the insulating sleeve 30 14. In parallel to the consumer are arranged a condenser 9 and an adjustable ohmic resistance 10.

The arc lengths of the stationary contact pairs 2, 2' and 3, 3' are dimensioned such 35 that in accordance with the graph represented by Fig. 4 they will remain in contact with their respective rotating contact arms only during a portion of the half wave or half cycle of the alternating current voltage 40 furnished by the transformer. In other words only during a portion of this half cycle the transformer secondary is connected with the consumer. During the remainder of the half cycle this connection is interrupted. Nevertheless, during this remaining 45 period a natural voltage reaction exists at the consumer, determined by the own capacity of the consumer and by the capacity of condenser 9. This voltage due to the 50 total capacity is equalized during the contactless period over resistance 10. Thereby this voltage at the consumer decays at a rate indicated by the curve e in Fig. 4. For the purpose of my invention, the arc lengths of 55 segments 2, 2' and 3, 3' and the value of the total capacity of the consumer's circuit and its total ohmic resistance are dimensioned relatively to each other such that when the 60 rectifier contact is broken, the reactance voltage of the consumer determined by the total capacity of its circuit coincides in time value with the voltage of the alternating current half wave. The particular values necessary to obtain this effect may be ascertained from 65 the equation (11). When the conditions

given by this equation are fulfilled, the effect is simultaneously obtained, that as shown in Fig. 4, the reactance voltage of the consumer also coincides in time value with the voltage existing at the time in the transformer secondary when the rectifier contacts are closed. Thereby the impact oscillations referred to hereinbefore are avoided.

My invention is thus not confined solely to the design of the rectifier itself for producing the voltage characteristics shown in Figs. 3 and 4, but the equalization of the pressures at the moment of switching in may be attained by correspondingly controlling the exponential curve through insertion of proper auxiliary reactances 9 and 10 referred to hereinbefore.

Various modifications and changes may be made without departing from the spirit and the scope of the invention, and I desire, therefore, that only such limitations shall be placed thereon as are imposed by the prior art.

I claim as my invention:—

1. In an arrangement for producing and feeding a consumer with pulsating direct current from high tension alternating current, in combination a mechanical rectifier comprising cooperating stationary and rotating contact elements in circuit with the alternating current supplied, the contact surface arc lengths of said elements being such that the circuit connection between said elements is interrupted before the end of the half cycle of the supplied alternating current is reached, a pulsating direct current consumer circuit connected with said elements and the consumer, said consumer circuit having capacity and ohmic resistance of suitable values to bring the reactance voltage of the consumer circuit due to its capacity in timely agreement with the voltage of the half cycle of the supplied alternating current existing at the time of contact break between said elements.

2. In an arrangement for producing and feeding a consumer with pulsating direct current from high tension alternating current, in combination a mechanical rectifier comprising cooperating stationary and rotating contact elements in circuit with the alternating current supplied, the contact surface arc lengths of said elements being such that the circuit connection between said elements is made only after the beginning of a half cycle of the supplied alternating current and is interrupted before the end of said half cycle, a pulsating direct current consumer circuit connected with said contact elements and the consumer, said consumer circuit having capacity and ohmic resistance of suitable value, to bring the reactance voltage of the consumer circuit, due to its own capacity, in timely agreement with the voltage of the half cycle of the supplied al-

ternating current existing at the time of contact break between said elements, and to bring the reactance voltage of the consumer circuit to a value equal to the momentary 5 value of the supplied half cycle voltage when the contact between said elements is made.

3. In an arrangement for producing and feeding a consumer with pulsating direct 10 current from high tension alternating current, in combination a mechanical rectifier comprising cooperating stationary and rotating contact elements in circuit with the alternating current supplied, the contact 15 surface arc lengths of said elements being such that the circuit connection between said elements is interrupted before the end of the half cycle of the supplied alternating current is reached, a pulsating direct current 20 consumer circuit connected with said elements and the consumer, said consumer having capacity and ohmic resistance, an auxiliary capacity and resistance in said consumer circuit, the capacity of said consumer 25 and said auxiliary capacity being suitably dimensioned to bring the reactance voltage of the consumer circuit due to its local capacity in timely agreement with the voltage of the half cycle of the supplied alternating 30 current existing at the time of contact break between said two elements.

4. In an arrangement for producing and

feeding a consumer with pulsating direct current from high tension alternating current, in combination a mechanical rectifier 35 comprising cooperating stationary and rotating contact elements in circuit with the alternating current supplied, the contact surface arc lengths of said elements being such that the circuit connection between said 40 elements is made only after the beginning of a half cycle of the supplied alternating current and is interrupted before the end of said half cycle, a pulsating direct current consumer circuit connected with said contact elements and the consumer, said consumer having capacity and ohmic resistance, an auxiliary capacity and resistance in said consumer circuit, the capacity of said consumer 45 and said auxiliary capacity being suitably dimensioned to bring the reactance voltage of the consumer circuit due to its total capacity in timely agreement with the voltage of the half cycle of the supplied alternating current existing at the time of 50 contact break between said two elements, and to bring the reactance voltage of the consumer circuit to a value equal to the momentary value of the supplied half cycle voltage when the contact between said elements is made.

In testimony whereof I affix my signature.

REINHOLD RÜDENBERG.
